UNITED STATES PATENT OFFICE

KURT AUGUST PETERS, OF SAN FRANCISCO, CALIFORNIA

MOLDING MACHINE FOR CONCRETE STEPS

Application filed December 14, 1927. Serial No. 240,024.

The present invention relates to improvements in molds, and its principal object is to provide a convenient mold for steps made of concrete or similar materials by means of which the step may be recast into the form desired, and may be readily finished during and immediately after the molding process. It is particularly proposed to form the mold of a number of cooperating sections which may be very easily assembled into the mold and may be easily taken apart without disturbing the material used for the step. It is further proposed to arrange the sections in such a manner that one of the sections may be detached while carrying the entire step, and thus serves as a convenient supporting means for the entire step, while at the same time access is had to the top and front surfaces of the step for finishing the latter. It is further proposed to provide convenient means for changing the operative size of the mold by introduction of suitable fillers. It is further proposed to provide a finishing trowel for finishing the front of the step, the trowel being formed to correspond to the vertical outlines of the front face of the step.

Further objects and advantages of my invention will appear as the specification proceeds.

The preferred form of my invention is illustrated in the accompanying drawings, in which

Figure 1 shows a plan view of my mold and the surrounding arrangement for handling the molded step;

Figure 2 an enlarged section taken along line 2-2 of Figure 1;

Figure 3 a perspective view of a trowel;

Figure 4 a fragmentary vertical section taken along line 4-4 of Figure 2;

Figure 5 a perspective detail view of one of the sections of the mold; and

Figures 6 and 7 perspective detail views of fillers adapted to be used in connection with the mold.

While I have shown only the preferred form of the invention, I wish to have it understood that various changes or modifications may be made within the scope of the

claims hereto attached without departing from the spirit of the invention.

In its preferred form, my mold comprises a back section 1, a front section 2, and two end sections 3 and 4. The back section 1 is supported on a base plate 6 and sets against posts 7 so that the back section is fixed in place. The length of this section corresponds substantially to the length of the step to be molded, and a cut-out is provided in its upper portion as shown at 8 to provide a nosing for the step to be formed.

The front section 2 is shown in perspective view in Figure 5, and comprises a bottom piece 9, a front wall 11 rising from the front edge thereof, a substantially horizontal portion 12 extending forwardly from the upper edge of the front wall 11, and a vertical flange 13 rising from the front edge of the section 12. The latter section may be made on a slight incline as indicated in Figure 2. A number of bracing elements 14 slant from the lower edge of the front wall 11 to the front edge of the section 12 to strengthen the entire section, and also for the purpose of allowing this section to be rolled forward on spaced rollers in the manner to be described hereinafter.

The front section may be set up against the rear section in the manner shown in Figure 2, and its front edge supported by a hinged board 16 pivoted to the front edge of the base as at 17, and recessed at 18 to support the mold section. This board may be actuated in any suitable manner as, for instance, by one or more rack rods 19 hinged near the upper edge of the board as at 21 and actuated by means of pinions 22 supported in a bracket 23. Any suitable device such as a roller 24 supported in a clip 26 may be used for holding the rack rod to the pinion. All of the pinions of the three sets shown in the drawing are mounted on a common shaft 27 operated by means of a handle 28.

When the board 16 is let down, its free edge contacts with an edge 29 of a table 31, both edges being cut on a slight slant so that the board 16 is supported by the table and forms a bridge between the base 6 and the table 31. Suitable rollers 32 are provided in the face 10c

of the board 16 and in the table 31 to allow the front mold section to ride thereon in the manner indicated in Figure 2.

For closing the ends of the mold, I provide angle irons 33 on the two end sections 3 and 4 and pivot the latter as shown at 34 to the ends of two bars 36, which latter extend below the base and are pivoted with their free ends to a lever 37 arranged midway of the mold and pivotally supported as shown at 38. The lever normally extends transversely of the mold for holding both end sections in closing position, but may be actuated for swinging both end sections away from the mold by a handle 39, the extremity of which is presented on one end of the mold so as to be within easy reach of the operator. This handle may be locked in position by means of a pin 41 extending through registering perforations in the handle and a stationary lug 42. The pin 34 is guided in a slot 43 in the fixed bracket 44. (See Figure 4.)

In case it is desired to produce a step of less depth than the regular mold would make, a filling bar 46 may be placed on the bottom piece 9, and in a similar manner a filler 47 may be provided adjacent the flange 13 to reduce the width of the step.

My mold is used as follows: The rear section 1 may be fastened in place permanently or, if different forms of rear sections are provided, they may be made for interchangeability. The front section 2 is placed up against the rear section so that the bottom piece 9 contacts in the manner shown in Figure 2 and the board 16 is swung upward by revolving of the handle 28 on the shaft 27 until it stands substantially vertical and allows the front edge of the front section 2 to rest on the recess thereof. If the specification of the step to be formed calls for different dimensions, the fillers 46 or 47 may be used. Next, the two end sections 3 and 4 are pushed up against the ends by operation of the handle 39 and are locked in place by the pin 41. The mold is now ready to receive the mixture, which may be concrete or any other similar material. After the form has been filled and tamped, the upper surface is smoothed off by means of an ordinary plasterer's trowel, and the mass is allowed to set. After it has set sufficiently to maintain its form, the board 16 is swung downwardly on its hinge by means of the rack rods 19, the pinions 22, and the shaft 27 until the board comes to rest against the table 31. The front section 2, losing its front support, drops on the base, the entire mass of material adhering to the front piece and separating from the back section 1. The front section may now be rolled forward over the rollers 32, which causes the step to be presented in the slanting position indicated in Figure 2.

It will be noted that the step is formed with a nosing, and in order to facilitate the finish-

ing of the front face of the step, I provide a special trowel shown at 48 in Figure 3, which comprises two off-set faces 49 and 51 arranged in parallel planes and interconnected by a slanting connecting piece 52. A handle 53 of suitable form is secured to the trowel. It will be seen that this trowel is made to follow the contour lines of the front of the step, and in order to finish the latter it is only necessary to carefully slide my special trowel along the same.

I claim:

1. In a mold of the character described, a base, a mold section thereon, a tiltable section adapted for cooperation therewith for forming a mold, a hinged member for propping the latter section and a table spaced from the base, the hinged member being disposed to form a bridge between the base and the table when dropped from a propping position.

2. A mold section of the character described, comprising a bottom piece, a front wall rising from the front edge thereof, a substantially horizontal section extending forwardly from the upper edge of the front wall, a flange rising from the front edge and a plurality of braces connecting the front edges of the bottom piece and the horizontal section and disposed to allow the mold section to ride thereon when the section is advanced over a roller conveyor.

3. In a mold for a step of the character described, a rear mold section, a combined front and bottom mold section adapted to co-operate therewith in forming a mold and having a large overhang so as to gravitate away from the rear section when unsupported and means for propping the overhang whereby the second mold section is held in position.

4. In a mold for a step of the character described, a rear mold section, a combined front and bottom mold section adapted to co-operate therewith in forming a mold and having a large overhang so as to gravitate away from the rear section when unsupported and a hinged member for propping the overhang whereby the second mold section is held in position.

5. In a mold for a step of the character described, a rear mold section, a combined front and bottom mold section adapted to co-operate therewith in forming a mold and made to gravitate away from the rear section when unsupported and a hinged member for holding the latter mold in position, the second mold section being formed with diagonal rails and the hinged member having rollers allowing the rails to ride thereon when the hinged member is swung downward.

KURT AUGUST PETERS.
